(57) **CLAIM**

I claim, the ornamental design for a chicken coop heater, as shown and described.

DESCRIPTION

FIG. 1 is a front right perspective view of a chicken coop heater showing my new design.

FIG. 2 is a right side view thereof;

FIG. 3 is a left side view thereof;

FIG. 4 is a front view thereof;

FIG. 5 is a top view thereof;

FIG. 6 is a bottom view thereof; and,

FIG. 7 is a rear view thereof.

The broken lines shown in the drawings are for the purpose of illustrating portions of the article and form no part of the claimed design.
